BURNER CONTROL APPARATUS AND
SYSTEM

Albert L. Judson, Beloit, Wis., assignor to Minneapolis-Honeywell Regulator Co., Minneapolis, Minn., a corporation of Delaware

Application December 7, 1932, Serial No. 646,080

19 Claims. (Cl. 158—28)

This invention relates to apparatus for automatically controlled systems, preferably automatically controlled heating systems, and it has reference to the construction, assembly, installation and circuit connections of such apparatus in systems for automatically controlling the operation of oil burners, and the like, for heating systems.

The apparatus heretofore developed for controlling the operation of systems of the character referred to and for providing the essential protective features in such systems has included a considerable number of separate devices requiring a great deal of skilled labor in installing the apparatus. Experience with different types of systems has shown that means must be provided for affording protection against numerous hazards and undesirable operating conditions, and the provision of such protective apparatus has led to a great complication of apparatus and connections in the systems now in use.

Accordingly, the present invention provides for improved apparatus of unit assembly, which I preferably term a lockswitch, and which may include a magnetically operated switch controlling the operation of the burner motor, a thermally actuated lockout mechanism incorporating a manual reset which serves as a safety device when ignition does not properly take place at the burner, and a number of switches actuated by changes in stack temperature and arranged to provide the desired sequence of operation of the oil burner itself or of other safety or operating controls. These switches may comprise a switch controlling the operation of the burner ignition and a pair of switches governing the functioning of the magnetically operated switch controlling the burner motor.

Broadly, an object of the invention is to provide a control system for heating apparatus in which the supply of fuel to a combustion chamber, or the operation of a burner motor, is controlled by a member which is moved from one position to another by the action of the magnetic flux set up in the secondary of a transformer when a circuit including said secondary is closed.

More specifically, the invention has for an object the moving of a member in control of the supply of fuel to a burner, by the inter-action of the magnetic fluxes established by current flow through the primary and secondary windings of a step-down transformer, and controlling the current flow through the secondary of the transformer in response to a heat condition which it is desired to control, such as room tempera-

ture, boiler or furnace temperature or boiler pressure.

A further object of the invention is the provision of an electrical control system for an electrically controlled fuel supply device, the circuit to which is controlled by a switch that is normally biased to open position and is moved to closed position by the inter-action of the magnetic fluxes produced by the concurrent energization of the primary and secondary coils of a step-down transformer and controlling the energization of the secondary coil in response to a heat condition which it is desired to control.

Another object of the invention is the moving of a fuel supply control switch to closed circuit position by the energization of an electro-magnetic coil when combustion is absent, and reducing the energization of said coil upon the establishment of combustion, preferably by the insertion of a resistance in series circuit therewith upon operation of a thermal switch responsive to combustion temperature.

Another object of the invention is the provision of an automatic electrical control system for a fuel burner in which provision is made whereby the control system supervises its own operation so that the supply of fuel is discontinued until manual intervention if the control system fails to operate properly.

Another object of the invention is to provide control apparatus for automatically controlled heating systems including fuel feeding means and actuating means therefor, in which the actuating means may be controlled by the current flow in a control circuit and a transformer provided with a secondary coil in the control circuit and a primary coil in the main power supply circuit so that the magnetic fluxes resulting from the energization of the transformer coils will be instrumental in influencing a relay armature to control the fuel feeding actuating means.

A still further object of the invention is to provide control apparatus of this type operating on the transformer relay principle in which certain control devices responsive to combustion conditions established by the burner are adapted to reduce the current flow through the secondary coil and thereby decrease the effective magnetic pull of the transformer core sufficiently to hold the relay armature in actuated position but to release the armature upon current failure or serious reduction of current in the line and prevent subsequent actuation of the armature for a timed period, after which the larger current flow through the secondary is restored.

In order to apprise those skilled in the art how to practice and construct the invention, I shall now describe a preferred embodiment thereof in connection with the accompanying drawings, in which:

Figure 1 is a front elevational view of an assembly of control apparatus designed in accordance with the present invention;

Fig. 2 is a perspective view of the relay armature carrying the burner motor switch, as shown in Fig. 1;

Fig. 3 is a view similar to Fig. 1, with certain parts omitted;

Fig. 4 is a vertical sectional view taken on a line 4-4 of Fig. 1;

Fig. 5 is a fragmentary detailed view of a portion of the control apparatus and circuit connections carried at the rear of the base;

Fig. 6 is a schematic representation of an improved system of circuit connections designed for use in connection with the apparatus disclosed in the previous figures;

Fig. 7 is a schematic representation of a modified system of circuit connections designed for the same use; and

Fig. 8 is a detail view of the carriage and switch of the thermally actuated lockout mechanism.

Referring first to Figs. 1 to 5, inclusive, of the drawings, the apparatus disclosed comprises a sheet metal member 5 forming a base plate for supporting the devices to be described presently, and also constituting the rear wall of a casing for said apparatus.

The member 5 is provided with a rearwardly extending flange 6 about its entire edge for reinforcing purposes. Any suitable cover may be furnished to complete the enclosure of the apparatus. In Fig. 4 a cover 7 is arranged to extend over the apparatus on base plate 5 and be secured thereto by screws 8 cooperating with angle members 9 fixed to this base plate. Terminal members 10, 11, 12, 13, 14, 15, 16, 17, 18 and 19 are carried by suitable supporting members 20 and 21 of insulation material at the front of the base 5, and, with the exception of terminal 12, which is a permanent connection, are provided with suitable screws for the attachment of circuit connections thereto. Terminals 10 and 11 are adapted to have a supply circuit connected thereto. Two electrodes of a mercury contactor 22 are connected between the terminals 10 and 12 by means of flexible connecting leads 23 and 24 and the terminals 11 and 12 are directly connected to the primary coil 25 of a transformer 26 by conductors 27 and 34 located at the rear of the insulation plate or terminal board 20. The terminals 13 and 14 are adapted to have connected thereto conductors extending to the motor or other actuating mechanism of an oil burner or similar device. The terminal 14 is connected to line terminal 11 by a conductor 14' located at the rear of the terminal board 20.

The electrodes of a mercury contactor 28 are connected by flexible conducting leads 29 and 30 to terminals 13 and 15. The electrodes of a mercury contactor 31 are connected between the terminals 12 and 13 by flexible conducting leads 32 and 33. Thus the terminal 13 is connected to the terminal 10 by the contactors 22 and 31 connected in series, while terminal 14 and the terminal 15 are adapted to have connected thereto conductors extending to the ignition device of the burner system. With this arrangement, it will be seen that the ignition circuit is connected to the supply conductors extending to the terminals

10 and 11 through the three switches 22, 31 and 28 connected in series.

The conductor 27 and the conductor 34 are disposed on the back of the terminal board 20, and extend from line terminal 11 and the terminal 12 to the primary winding 25 of transformer 26 that is utilized to supply current at a reduced voltage to certain of the control apparatus to be described. The frame of this transformer is preferably secured directly to the base plate 5 by screws 35, the base plate 5 being suitably cut away as indicated at 37 (Fig. 5) to provide room for the primary winding 25 of the transformer. The base plate 5 is also cut away at 38 to provide room for the secondary winding 39 of the transformer, said cut-away portions 37 and 38 being clearly shown in Fig. 5. One terminal of the secondary winding 39 is connected through a conducting lead 40 to the terminal 16, this conducting lead extending upwardly from the secondary winding at the back of base plate 5, and extending through an aperture 41 to connect to this terminal 16. The other terminal of this secondary winding is connected through a conducting lead 42, also disposed at the back of base plate 5, connecting screw 43 and a flexible lead 44 to one of the two electrodes of a mercury contactor 45.

The other electrode of the contactor 45 is connected through a flexible lead 46 to a terminal 47 connecting by a flexible lead 48 to a terminal 49 of an electrical heating element 50. The other terminal 51 of the heating element 50 is connected through a flexible lead 52, disposed on the back of base plate 5, to the binding post 53, to which may be connected one of the terminals of a limit control 53 hereinafter to be described. The flexible lead 52 extends through an aperture 55 in base plate 5, as shown in Figs. 1 and 3, to connect with binding post 18.

A terminal screw 56 is located upon base plate 5 adjacent to the terminal screw 43 and is connected through a flexible lead 57 to one of two electrodes of a mercury contactor 58. The other electrode of contactor 58 is connected through a flexible lead 59 to the terminal 47.

As illustrated in Fig. 5, terminals 47 and 51 extend through the base plate 5, and an insulation strip 60 is secured in position by rivets 62 extending through base plate 5. Terminals 43 and 56 likewise extend through the base plate 5 and insulation mounting 60 and secure in position an insulation plate 63, comprising, together with a winding 64, a hold resistor connected between the terminals 43 and 56, this being clearly shown in Fig. 5.

An auxiliary secondary winding, together with certain of the controls described, constitutes an ultimate safety secondary circuit having a flexible lead 65 connecting to the terminal 56 and a flexible lead 66 connecting to the binding post 19, to which is connected one of the contacts of the limit control 53, both flexible leads 65 and 66 being disposed at the rear of the base plate 5.

The contactor 31 controlling the circuit of the motor or other actuating means for the burner is mounted for pivotal movement upon an arm 67, which arm is connected by a screw 68 to a relay armature designated broadly as 69. The relay armature 69 is mounted for pivotal movement at 70, shown in Fig. 3, adjacent to the core 71 of transformer 26. Core 71 may be of any suitable construction, which as shown in the drawings, comprises the plurality of laminated bars 72 secured together in rectangular formation to allow

the primary coil 25 and an ultimate safety secondary coil 172, (shown in Figure 4) to be hereinafter described, to be wrapped thereabout along one leg and the secondary coil 39 to be wrapped about one of the shorter legs and at right angles to primary coil 25 and the said secondary coil 172.

The laminated bars 72 of core 71 are secured together to form a transformer frame that is secured to base plate 5 by screws 35. Rivets 73 may also be used at various points along the core to maintain bars 72 as a rigid unit. The pivotal movement of relay armature 69 at 70 tilts contactor 31 either to open or closed position. A weight 74 may be secured by a screw 75 to the free end of the bar 67, and the relay armature 69 allowed to tilt counterclockwise by gravity about the point 70 when the transformer is deenergized by a failure or serious reduction in the line voltage that would prevent proper functioning of the burner and its control parts. Shading pieces 76 are provided at the free end of the relay armature 69 to eliminate the vibration or humming of the armature which would normally occur from the use of alternating current.

25 A bracket 77 is secured by the screw 68 to the armature 69 with its arm 78 acting as a stop for the armature by engaging any suitable part, say the upper edge of the upper leg of the core 71, to limit the movement of the armature when tilted counterclockwise by the gravity action of weight 74.

The detail construction of the transformer relay and its armature may be changed to meet particular requirements. The invention is mainly directed to utilizing the flow of current through a transformer relay to actuate the switch 31 controlling the burner motor or other control device. Any suitable type of armature may be provided as long as relative movement is obtained to effect an actuating movement of say the motor switch 31.

The various elements of the apparatus shown in the drawings have been generally described above, and the detail of construction and assembly of these elements will now be described. The mercury contactors 28 and 45 are carried by clips or holders 80 and 81, respectively, (see Fig. 4) and these clips are secured to downwardly and upwardly extending arms of a member 82 that is centrally perforated to permit the extension of an actuating rod 83 therethrough. The central portion of the member 82 is cup-shaped to receive the forward extremity of a compression spring 84, the rear extremity of which is received by a cup member 85.

55 The periphery of the cup member 85 is forwardly presented or flanged and the member itself is fixed upon one end of a sleeve 86 loosely mounted upon rod 83. Sleeve 86 extends through the aperture in the cup-shaped portion of member 82, and a frictional washer 87 is preferably provided between the forward extremity of the spring 84 and the inner surface of this cup-shaped portion of member 82, while a similar washer is preferably disposed between the rear extremity of spring 84 and the cup-member 85. A washer 86a is secured to the front end of sleeve 86 and forward of the member 82 whereby the washed 86a, sleeve 86 and cup member 85 form a unitary structure and the member 82 is spring pressed against washer 86a by means of the coiled spring 84 which is confined between member 82 and cup member 85. As the result, the member 82 normally rotates with the sleeve 86 but may be restrained from so moving during movement of the sleeve 86 by reason of the frictional slip connection provided by the

spring 84 pressing the member 82 against the washer 86a. Thus, a frictional slip connection is provided between the rod 83 and the member 82 to which the mercury contactors 28 and 45 are secured.

5 A similar arrangement is provided between the rod 83 and a member 90, to which the mercury contactor 58 is secured by means of a clip or holder 91. This arrangement comprises a sleeve 97 which loosely engages the rod 83, a cup member 92 which is secured to one end of sleeve 97 and a washer 97a which is secured to the other end thereof. Member 90 is mounted loosely on sleeve 97 and is formed with a cupped portion which receives one end of a compression spring 15 93, the other end of which abuts cup member 92 whereby member 90 is pressed against washer 97a. Preferably, frictional washers 94 and 95 are placed between the ends of spring 93 and cup member 92 and the cupped portion of member 90. 20 By this arrangement, member 90 normally rotates with sleeve 97 but may remain stationary if constrained against movement with sleeve 97 since the spring 93 pressing member 92 against washer 97a forms a slip frictional connection 25 therebetween.

A collar 96 is secured to rod 8. Sleeves 97 and 86 are next loosely placed on the rod 83 and a nut 98 is threaded on the extremity of rod 83 and turned down tightly against sleeve 86 whereby 30 sleeves 86 and 97 are held between collar 96 and nut 98 and must therefore move in conformity with the movements of rod 83.

A collar 99 is adjustably secured by a screw 100 to rod 83. A sleeve member 101 extends 35 rearwardly from a heat insulating shield plate 102 mounted at the rear of face plate 5 by a plurality of screws 103 threading into mounting posts 104 rigidly fixed to the rear face of mounting plate 5. Detachable means, such as bolts 40 106, may be used to secure sleeve 101 in position. The rear extremity of sleeve 101 receives the foremost portion of a coiled bimetallic or other suitable thermostatic element 107, and the end of the element 107 is secured to the sleeve 101 by 45 means of a screw 108, passing through an angle guide 109, interiorly disposed in sleeve 101 and apertured at 110 to allow rod 83 to pass therethrough. From this point the thermostatic element 107 extends rearwardly for a substantial 50 distance whereby this exposed portion of the element may be disposed within a stack or flue of the furnace to render said element responsive to conditions of combustion in the furnace.

The rod 83 extends rearwardly through the 55 entire length of sleeve 101 and the thermostatic element 107 is in axial relation to these members and is angularly bent at its rearmost extremity. This angularly bent portion of the element 107 is secured to the extreme outer end of the rod 83 60 by a screw 111 and a nut 112 for firmly securing the rod 83 to the end of the thermostatic element 107.

It will be understood that when the thermostatic element 107 is subjected to varying temperatures due to different conditions of combustion in the furnace or combustion chamber to be controlled by the system, the rearward extremity of this thermostatic element is rotated by reason of the expansion and contraction of its coils. This rotation is transmitted directly to rod 83 and thus to a limited extent to members 82 and 90 which support the mercury contactors or switches 28, 45 and 58. The limitation of movement of the members 82 and 90 is permitted 70 75

by reason of the frictional slip connections between these members and the rod 83 as above described. These limitations are definitely fixed by stop members 113, 114, 115 and 116, which are 5 adapted to be engaged by members 82 and 90 in different positions thereof. The stop members 113, 115 and 116 are adjustable in slots 117 and 118. The stop member 114 is fixed in its position on face plate 5. Stop members 113 and 116 10 constitute projections in the path of movement of member 82 and are adjustable to predetermine the movement of member 82 by the thermostatic element 107 before the slip connection between the member 82 and the rod 83 is effective to permit continued rotational movement of rod 83 by the thermostatic element 107. Stop member 115 15 is adjustable in slot 118 likewise to predetermine the movement of member 90 carrying the contactor 58 before its frictional slip connection becomes effective to allow continued movement of rod 83 by the thermostatic element 107.

It will be seen that stop members 113 and 114 20 adjustably limit the extreme counterclockwise position of members 82 and 90, respectively, and 25 the stop members 116 and 115 adjustably limit the clockwise movement of members 82 and 90, respectively. The thermostatic element 107 is so arranged that the rod 83 is rotated in a clockwise direction, as viewed in Fig. 1, as this thermostatic element is heated. Cooling of the member 107 thus obviously effects counterclockwise rotation of the rod 83, as viewed in the same figure. While the member 107 is relatively cool, therefore, which condition corresponds to the 30 absence of combustion in the furnace or combustion chamber that is to be controlled, the members 82 and 90 are in their extreme counterclockwise positions as shown in Figs. 1 and 3. When these members occupy such positions the container for each of the mercury contactors 28, 45 and 58 is tilted downwardly to the left as shown. Each of the contactors comprises a single pair of electrodes, the electrodes in the contactors 28 and 45 being located in the left-hand extremities 45 of the respective containers so that both of these switches are closed in this position. The electrodes of contactor 58 are located in the right-hand extremity of the container so that this switch is opened in its left-hand position, as 50 shown in Figs. 1 and 3.

The temperature of the thermostatic element 107 is raised due to the establishment of combustion in the furnace or combustion chamber to be controlled. The rod 83 is gradually rotated 55 in clockwise direction, as viewed in Fig. 1. After a predetermined extent of such rotation, the switch 58 is tilted to such an extent that the body of mercury therein is caused to flow from the left-hand extremity of its container to the 60 right-hand extremity thereof, thus closing the circuit connection between conductors 51 and 59. This action precedes that of the switches 28 and 45, because the angle of inclination of the container for the switch 58, in a direction downward and to the left, as viewed in Fig. 1, is less 65 in the extreme counterclockwise position than is the angle of inclination of the switches 28 and 45. After the switch 58 is moved to closed circuit position, the member 90 which supports said 70 switch engages the adjustable stop 115 whereby further movement of the switch 58 and the member 90 is prevented.

As the rotation of rod 83 continues, the circuit 75 between the two electrodes of switch 45 is next opened, which electrodes are connected across

a circuit comprising the resistor 64 and the two electrodes at the right-hand extremity of switch 58, to which latter electrodes the conductors 51 and 59 are respectively connected. The opening of the switch 45 is brought about subsequently to the closing of the switch 58 by reason of the curved or humped formation of the container for the switch 45 and for the further reason that it is inclined further to the left.

As the rotation of the rod 83 continues further, and after switch 58 has closed and switch 45 has opened, the switch 28 is tilted to such an extent that the body of mercury within its container is moved from the left-hand extremity of said container to the right-hand extremity to 15 interrupt the circuit connection between the conductors 29 and 30, which are respectively connected to the two electrodes in the left-hand extremity of the container for this switch 28. The opening of the circuit between the electrodes 20 of switch 28 interrupts the ignition circuit of the burner control system, as will hereinafter appear in connection with the description of the entire system of circuit connections.

As the rotation of the rod 83 continues further, and after the switch 58 has closed, the switch 45 has opened and the switch 28 has opened then the movement of member 82, which supports switches 45 and 28, is arrested by engagement of the upper portion of this member with the stop 30 116. When the two members 90 and 82 have been thus actuated in sequence to their extreme clockwise positions, as determined by the adjustable stops 115 and 116, respectively, further movement 35 of the thermostatic element 107 in response to a further increase in temperature of said thermostatic member is ineffective to cause any further movement of the switches carried by members 82 and 90, and it is during this condition that the frictional slip connections between the rod 83 40 and the members 82 and 90 are effective.

Upon cooling of the thermostatic element 107, however, the direction of the rotation of rod 83 is immediately reversed and the immediate actuation of the members 82 and 90 toward their original positions, as shown in Figs. 1 and 3, is initiated. The switch 58 first opens and the member 90, in moving through a relatively short arc, engages the stop pin 114. Next, the switch 28 moves to closed circuit position and thereafter the switch 45, after an appreciable interval of time, as measured from the opening of the switch 58, moves to closed circuit position and the member 82 engages the adjustable stop pin 113. The arc of movement allowed to the 55 switches 45 and 28, as measured by the distance between the adjustable stop pins 116 and 113, is substantially greater than the arc of movement allowed to the switch 58 which is measured by the fixed stop pin 114 and the adjustable stop pin 115. The hump formed in the container of the switch 45 further serves to delay the closing of the circuit through this switch as the switch is moved in a counterclockwise direction upon the cooling of the thermostatic element 107. The 60 reasons for providing the aforementioned sequence of operation of the switches 58, 28, and 45 will hereinafter appear.

The container tube of switch 22 is embraced by a clip or holder 120 that is secured to a 70 pivotally mounted member 121. (See Figs. 3 and 8.) The latter member is journaled upon a pin or rod 122 carried by and extending forwardly of base plate 5. A pin 123 is used to permit member 121 to be easily removed from 75

pin 122. The member 121 has horizontally extending apertured lugs 124 and 125. The aperture in lug 125 is screw-threaded to receive a threaded portion of a vertically extending pin 126, this pin also passing through the aperture in lug 124. A collar 127 is fixed to pin 126 to act as an abutment for one extremity of a spring 128, the opposite extremity of spring 128 abutting against lug 124. A slotted head 129 at the lower end of pin 126 allows vertical adjustment of pin 126. Arm 130 is extended to carry clip 120 embracing the container tube of switch 22 a distance beyond the pivotal mounting pin 122 sufficient to allow the weight of the container 15 to cause contactor 22 normally to tilt by gravity clockwise. The two electrodes of switch 22 being located near the left-hand end of the container, it will be seen that this switch will be closed when it occupies the normal position 20 shown in Figs. 1 and 3. The gravity action tending to tilt switch 22 clockwise or to the right and to cause the body of mercury in the container of this switch to move to the right and open the circuit at the electrodes, is normally restrained by a forwardly extending leg 25 132 of a bimetallic element 133.

Upon a predetermined upward deflection of the bimetallic element 133, however, the extremity 30 132 moves out of the path of the upper end of pin 126, whereupon the action of gravity upon switch 22 causes this switch to move pivotally about the rod or pin 122 in a clockwise direction, as viewed in Figs. 1 and 3. Such movement causes the switch 22 to be tilted downwardly to 35 the right, whereby the mercury within the container is moved to the right-hand extremity to open the circuit through the two electrodes of this switch. The upward deflection of the bimetallic member 133 is effected by an increase 40 in the temperature thereof in response to energization of the electrical heating element 50 in the manner which will appear hereinafter. For the purpose of rendering this part of the apparatus independent of ambient temperatures, the bimetallic element 133 is supported by means of 45 screws 135 forming, with a spacing collar 136 and nuts 137, a connection with the left-hand extremity of a second bimetallic element 138. (See Fig. 3.) The latter bimetallic element is 50 rigidly supported upon a forwardly extending portion 139 of bracket member 140. The bimetallic member 138 operates in a manner opposite to that in which the member 133 operates, that is, the right-hand extremity of the member 55 138 is deflected downwardly in response to a rise in temperature.

The two bimetallic elements 133 and 138 are so proportioned that the deflections effected by 60 changes in ambient temperatures will exactly balance one another and will have no effect whatever upon the position of the left-hand extremity of the bimetallic element 133. The heating element 50 is disposed to effect the bimetallic member 133 without affecting the member 138. Heating element 50 is carried upon brackets 141 and 142, riveted at 62 and 49, respectively to the insulation plate 60 secured at the rear face of base plate 5. (See Fig. 5.)

70 The portion of the base plate 5 cut away as indicated at 37 to provide room for the primary winding 25 is slightly enlarged, as indicated at 143, to allow for the connection of brackets 141 and 142 to the insulation plate 60. A horizontal heat insulating plate 144 is carried between the

brackets 141 and 142 and directly below heating element 50.

Referring now to Fig. 6, two current supply conductors 146 and 147 are shown, it being understood that these conductors will be respectively connected to the line terminals 10 and 11 carried by the terminal board 20 of the control apparatus, as heretofore described in connection with Fig. 1. A motor or other burner actuating apparatus 148 is connected in the circuit by means of conductors 149 and 150, which will be respectively connected to the motor terminals 13 and 14, as shown in Fig. 1. Connections to an ignition device 151 are made through a conductor 152 and 152' connected to terminals 15 and 14, respectively.

The terminals 16, 17 and 18 are located in the control circuit between the conductors 40 and 52 to facilitate the connection of a room thermostatic switch 155 and the switch 53 of the boiler control or similar device in the circuit. In Fig. 6 of the drawings, the room thermostatic switch is diagrammatically shown and the switch of the boiler control or similar device is diagrammatically shown, these two switches being connected 20 in series relation to each other by the conductors 156 and 157. The other terminal of the room thermostatic switch 155 is connected to the conductor 40 by means of a conductor 158, and the other terminal of the switch of the boiler control or similar device is connected to the conductor 52 by means of the conductor 159.

The remaining connections of the control circuit, as described in connection with Fig. 1, comprises a series circuit extending from the conductor 52 through the lockout resistor 50 and conductor 48, the terminal 41, conductor 46 through the recycling or pull switch 45, the conductor 44, terminal 43 and the conductor 42 to the opposite transformer secondary terminal. 35 The operation of the control system connected according to Fig. 6 is normally controlled by the room thermostatic switch 155, which is arranged in any well known manner to be responsive to the temperature of the room to be heated.

Operation

Referring to Fig. 6, it will be noted that the primary winding 25 of the transformer 26 is normally constantly energized by the following circuit: Current flows through the conductor 146, terminal 10, conductor 23, lockout switch 22, conductor 24, terminal 12, conductor 34, the primary winding 25 of the transformer 26, conductor 27, terminal 11, and line conductor 147. It is customary to supply with controls for oil burner motors a low water cut-off device which is shown diagrammatically at 173 and, in the event that such a safety device is applied, then the same may be connected in advance of the binding post 10. This energization of primary winding 25 establishes a magnetic flux which travels unrestrictedly through the core 11 and does not operatively influence the armature 69. Assuming the boiler conditions to be normal so that electrodes 160 and 161 of the limit control switch 53 are bridged by the mercury therein, when the room temperature falls to a predetermined point so as to close room thermostat 155, a circuit through the relay secondary 39 will be completed 60 as follows: Secondary 39, conductor 42, terminal 43, conductor 44, switch 45, conductor 46, terminal 47, conductor 48, lockout resistor 50, conductor 52, terminal 18, conductor 159, electrodes 161 and 160 of the limit control switch 53, 65

conductor 157, terminal 17, conductor 156, room thermostat 155, conductor 158, terminal 16, and conductor 40 to the other side of secondary 39. Completion of this circuit through relay secondary 39 establishes a magnetic flux which opposes the magnetic flux set up by primary winding 25 with the result that some of this flux from the primary winding 25 must travel through armature 69. This diverting of the magnetic flux 5 through armature 69 attracts the free end of armature 69 and moves it into engagement with the core 71 whereby motor switch 31 is tilted to its closed circuit position to establish a motor energizing circuit which is as follows: Line 146, terminal 10, conductor 23, lockout switch 22, conductor 24, terminal 12, conductor 32, motor switch 31, conductor 33, terminal 13, conductor 149, motor 148, conductor 150, terminal 14, conductor 14', terminal 11, and line 147.

20 An oil valve 160 may be connected in parallel with motor 148 if it is desired to use an oil valve in the control system.

Closure of motor switch 31 likewise establishes an ignition circuit which starts at the terminal 25 13 and flows through conductor 29, ignition switch 28, conductor 30, terminal 15, conductor 152, ignition device 151, and conductor 152' to the terminal 14.

Energization of the motor 148 and ignition 30 means 151 (and an oil valve 160 if used) supplies fuel to the combustion chamber and attempts to ignite the same. If combustion should not be established the heat generated by lockout resistor 50 will heat bimetallic element 133 to such an 35 extent at the end of a predetermined time, that the end 132 thereof will move out of engagement with the end of pin 126 thereby allowing lockout switch 22 to tilt in a clockwise direction about the pivot 122 under the influence of gravity to open 40 the circuit through lockout switch 22. If this happens the energizing circuits for the motor 148, oil valve 160, ignition means 151, and the primary winding 25 of transformer 26 will all be interrupted and the control system will be rendered 45 inoperative until lockout switch 22 is re-closed manually by operation of a manual reset comprising a button 165.

The opening of switch 22 in this manner interrupts the control circuit and terminates the operation 50 of the heating system. Consequently, when the lockout switch 22 is open, current can no longer flow to any part of the system, and in order to re-establish any operation in the system, it is necessary to reset the lockout switch 55 22, say, by means of a manual reset comprising a button 165. The button 165 may be manually reset without removing the cover 7 of the casing and is constructed so that it cannot be operated except by being manually turned. The button 60 165 extends upwardly through lower flange 6 of base plate 5, and the base plate 5 is cut away at 166, with the cut-away portion struck down at 167 to form a bearing for the pin 168 to which this button is attached. An actuating pin 169, 65 fixed to pin 168, extends horizontally forward through the cut-away opening 166 to engage the head 129 on the lower end of pin 126. The manual turning of button 165 clockwise or to the right 70 swings operating pin 169 against this head 129, whereby to swing the pivotally mounted member 121 upwardly about pivot 122 and tilt the lockout switch 122 to the left to close the circuit at its electrodes.

If the trouble causing the failure of combustion 75 establishment has been remedied, the stack ther-

mostatic element 107 will respond to the rise in temperature in the stack, and cause rod 83 to rotate and close the hold switch 58 and open the pull switch 45, whereafter the ignition switch 28 will open and the system will operate normally until the room temperature is satisfied and the thermostat 155 is opened. Should combustion fail to be established after the manual reset button 165 is operated to close the lockout switch 22, the stack will remain cold and the thermostatic element 107 will not operate. The current will continue to flow through the heat coil 50, to effect another lockout operation of the switch 22. It will be promptly determined, therefore, whether the trouble causing the lockout has been corrected.

Assuming that the fuel supplied by motor 148 is properly ignited by ignition means 151, thermostatic element 107 will begin to heat and, as previously described, will first move switch 58 to 20 circuit closed position. Movement of switch 58 to closed position establishes a circuit from terminal 43 through hold resistor 64, terminal 56, conductor 57, switch 58, and conductor 59 to terminal 47. It will be noted that this circuit through hold resistor 64 is shunted by the circuit through switch 45 previously described.

Further heating of thermostatic element 107 will thereafter move switch 45 to open circuit position thereby removing the shunt around hold 30 resistor 64 and switch 58 whereupon the circuit through relay secondary 39 will be as follows: Conductor 42, terminal 43, hold resistor 64, terminal 56, conductor 57, switch 58, conductor 59, terminal 47, conductor 48, lockout resistor 50, 35 conductor 52, terminal 18, conductor 158, electrodes 161 and 160 of limit control switch 53, conductor 157, terminal 17, conductor 156, room thermostat 155, conductor 158, terminal 16, and conductor 40 to the other side of relay secondary 40 39. It will be noted that hold resistor 64 is now in series circuit relationship with lockout resistor 50. This reduces the current flow through lockout resistor 50 to such an extent that the heat generated thereby is insufficient to move the end 45 132 of bimetallic element 133 out of engagement with pin 126. In other words, insertion of hold resistor 64 in series with lockout resistor 50 operatively de-energizes lockout resistor 50 and consequently prevents the lockout switch 22 from 50 moving to open circuit position.

Continued heating of thermostatic element 107 moves ignition switch 28 to open circuit position thereby de-energizing the ignition means 151.

The system is now operating normally to supply heat to the room and under normal conditions will continue to so operate until room thermostat 155 opens the circuit through relay secondary 39. Of course, if the boiler temperature or pressure should become excessive, limit control switch 53 will be operated to move its mercury from its bridging relationship with terminals 160 and 161. This action likewise would open the circuit through relay secondary 39. If 60 the water in the boiler should become too low, the low water cut-off switch 173 would open the main line circuit to conductor 146 and discontinue operation of motor 148.

If there should be a flame failure—that is, if 70 the flame should become extinguished after having been initially successfully established—thermostatic element 107 will begin to cool and immediately move switch 58 to open circuit position thereby interrupting the circuit through 75

relay secondary 39. Whenever the circuit through relay secondary 39 is interrupted, the magnetic flux set up by primary winding 25 will no longer be diverted through armature 69, and the weight 74 will tilt armature 69 in a counterclockwise direction to open motor switch 31. Opening of motor switch 31 discontinues the supply of fuel to the combustion chamber. Continued cooling of thermal element 107 causes member 90 to engage stationary stop 114 and thereafter closes ignition switch 28. Closure of ignition switch 28 will not re-energize ignition means 151 since motor switch 31 is still open. Further cooling of thermal element 107 will, after 10 a time interval measured from the opening of switch 58, close switch 45 whereupon the circuit through relay secondary 39 will be again completed in the manner hereinbefore mentioned. The system will therefore again attempt to establish 15 combustion in the usual manner. The time interval between the opening of switch 58 and the re-closing of switch 45 provides a standby period during which any hot oil vapors that may be present in the combustion chamber will be dissipated so as to eliminate the possibility of an 20 explosion when the ignition is re-established.

If there should be a momentary failure in the supply of electrical power while the system is operating to supply heat, all of the circuits will 25 be interrupted and the motor switch 31 will return to open circuit position. The thermostatic element 107 will begin to cool but if the supply of power is resumed before switch 58 has been moved to open circuit position, the series 30 circuit through relay secondary 39, hold resistor 64, and lockout resistor 50 will allow such a small flow of current through the relay secondary 39 that the flux diverted through armature 69 will be insufficient to move the armature 69 in a 35 clockwise direction to close the circuit through motor switch 31. Therefore, the system will remain inoperative until switch 45 is closed, after a time interval as a result of substantial cooling 40 of thermostatic element 107, in a manner similar to that hereinbefore pointed out in respect to a 45 flame failure.

Ultimate safety

The control system that constitutes the present invention provides means by which faulty 50 operation of the control system itself is checked.

A safety circuit, which may be termed herein as an ultimate safety circuit, is provided to protect the system against the failure of the control apparatus itself to function properly. This ultimate safety circuit includes, as shown in Fig. 6, a third electrode 170 of the limit control 53, an ultimate safety secondary 172, the hold switch 58, and the lockout resistor or heat coil 50. The third electrode 170 connects by means of a flexible conductor 171 to the terminal 19, and this terminal 19 connects to the ultimate safety secondary 172 by means of a flexible conductor 66 extending through the aperture 55 in the base plate 5, and connecting to this secondary coil 172 55 at the back of the base plate 5.

With the control system operating normally, the room thermostat 155 may open the circuit through relay secondary 39 as a result of rise in room temperature, but the armature 69 may 60 fail to move the motor switch 31 to open circuit position. Also the room thermostat 155 may fail to open the circuit through relay secondary 39 because of faulty contact operation within the room thermostat 155. Under either of these 65 conditions the boiler temperature or pressure 70 conditions the boiler temperature or pressure 75

will become excessive so as to move switch 53 to a position in which the mercury contained in switch 53 will bridge electrodes 161 and 170. Bridging of electrodes 161 and 170 of switch 53 will establish the following circuit: Ultimate 5 safety secondary 172, terminal 56, conductor 57, switch 58, conductor 59, terminal 47, conductor 48, lockout resistor 50, conductor 52, terminal 18, conductor 159, electrodes 161 and 170, switch 53, conductor 171, terminal 19, and conductor 66 10 to the other side of ultimate safety secondary 172. This circuit will operatively energize lockout resistor 50 which, in turn, will heat bimetallic element 133 to cause the end 132 thereof to move within a predetermined time out of engagement with pin 126 thereby allowing lockout switch 22 to move to open circuit position under the influence of gravity. The movement of lockout switch 22 to open circuit position will render the entire control system inoperative until manually reset, as hereinbefore described. This same operation will result even though some of the mercury in limit switch 53 continues to bridge electrodes 160 and 161 while another portion of the mercury bridges electrodes 161 and 170. By 20 25 this arrangement it will be seen that this control system supervises its own correct operation.

The modified system of circuit connections shown in Fig. 7 is designed to provide the same 30 operating and protective features that are obtained with the system illustrated in Fig. 6, but certain minor changes in the circuit connections of the ultimate safety circuit are shown to illustrate the fact that this ultimate safety circuit is not limited to the use of a separate ultimate safety secondary coil 172 as shown in Fig. 6. The relay secondary coil 39 may be employed in the ultimate safety circuit by providing an ultimate safety resistor 176, a four-wire hold switch 177 being used instead of the two-wire hold switch 58 and a two-wire limit control 178 being used instead of the three-wire limit control 53. The hold tube 177 is preferably a double ended contactor tube having a pair of electrodes at each end with one of the electrodes of one pair arranged also to complete the circuit with one of the electrodes of the other pair. Electrodes 180 and 181 complete the circuit during initial operation and before the stack thermostatic element 107 has responded to the rise in temperature in the stack 50. Electrodes 182 and 183 complete the circuit of the ultimate safety circuit to operatively de-energize the transformer relay and thereby allow the motor switch 31 to open when either the room thermostat 155 or the limit control 178 55 opens. If the motor switch 31 should stick and not open the circuit of the motor 148 when either the room thermostat 155 or the limit control 178 opens, the ultimate safety resistor 176 then functions as a heater for the bimetallic element 133 60 of the thermally operated lockout mechanism, in lieu of the lockout resistor or heater 50, to effect a permanent lockout of the apparatus by opening the lockout switch 22.

It will be understood that the ultimate safety 65 resistor 176 may be suitably located, as is the heater 50, in thermal relation to bimetallic element 133, to cause warping of the latter and a consequent releasing of pin 126 to tilt the lockout switch 22 to open position when the current flows through the ultimate safety resistor 176 for a predetermined time interval. When combustion is established and the stack thermostatic element 107 has responded to the rise 70 in temperature in the stack to rotate rod 83 75

clockwise, the hold tube 177 is tilted to the right to cause the mercury to bridge electrodes 181, 182, 183, and thereafter the pull switch 45 is opened. The circuit thus completed through the 5 electrodes 181 and 183 and the hold resistor 64, will reduce the quantity of current flowing through the secondary coil 39. This reduced current flow in the secondary coil 39 will, in turn, reduce the effective magnetic force holding the relay armature 69 in such position as to hold the motor switch 31 closed, but this reduced magnetic force still continues to hold the motor switch 31 in closed position.

Considering now the condition following closing 15 of the room thermostat 155, the current will flow from secondary 39, through wire 184, limit control 178, wire 185, room thermostat 155, wire 186, electrodes 181 and 180 of hold tube 177, wire 187, pull tube 45, lockout resistor 50, wire 20 188, and back to the secondary coil 39. In the same manner as previously described in connection with the showing of Figs. 1 to 6, inclusive, the flow of current in the secondary coil 39 causes the magnetic force to actuate the relay 25 armature 69 and close the motor switch 31. The ignition will be energized.

If combustion is not established in the furnace or combustion chamber within a suitable interval of time after the closing of the motor circuit, the lockout switch 22 will be opened at the end of such interval by reason of the fact that the thermostatic element 107 remains cold in the stack and does not rotate rod 83 and tilt hold switch 177 and, thereafter open the pull switch 45 to deenergize the lockout resistor 50. Upon failure of the hold switch 177 to open the circuit described at electrodes 180 and 181 and the pull switch 45 to open, current flowing through the heating resistor 50 for a predetermined period 40 will cause the bimetallic element 133 to warp. The warping of the bimetallic element 133 raises its arm or leg 132 out of the path of pin 126 and the action of gravity causes switch 22 to tilt clockwise about its pivot 122 for the purpose 45 of breaking the circuit between the electrodes of this switch, the primary circuit being thereby opened as shown in Fig. 7.

In order to carry out the safety lockout feature requiring manual resetting of the apparatus if 50 switch 22 is opened by the action of the thermally operated element 133, button 165 is provided, but it will be understood that broadly, in connection with both variant embodiments of the invention herein shown and described, the manual resetting is preferable but not essential to the novelty of the other features described.

If combustion is established, the hold switch 177 will establish a holding circuit for the secondary coil 39 in which the current will flow from 60 the secondary coil 39, through wire 184, limit control 178, wire 185, thermostat 155, wire 186, electrodes 181 and 183 of hold tube 177, wire 189, hold resistor 64, and back to the secondary coil 39.

65 The hold resistor 64 will reduce the flow of current flowing through the secondary coil 39 and thereby reduce the effective magnetic force on the armature 69, as hereinabove described in connection with the circuit shown in Fig. 6. 70 The armature 69, in the event of power failure is thus immediately released, and in the event of flame failure is released as the thermal element 107 cools and tilts switch 177 to the left to open the circuit through the electrodes 181 and 75 183. The motor switch 31 cannot be reclosed by

the armature 69 until the power has been restored and/or the pull tube 45 closes, as described in connection with Fig. 6.

When the room thermostat 155 is satisfied or 5 the boiler pressure or temperature becomes excessive, the room thermostat 155 or limit control 178 will open the above described holding circuit. The current flow may then be traced from the secondary coil 39, ultimate safety resistor or 10 heater 176, wire 190, electrodes 182 and 183 of hold tube 177, wire 189, hold resistor 64, back to the secondary coil 39. Energization of heating coil 176 will heat bimetallic element 133 and the current flowing through resistance 64 and 15 heating element 176 reduces the effective magnetic force on armature 69 to such an extent that the motor switch 31 should move to open circuit position. If motor switch 31 does open, the stack will immediately cool and open the 20 circuit between electrodes 182 and 183 of the hold tube 177 which causes complete deenergization of the resistor 176. If the motor switch 31 should stick in closed position or the motor should otherwise fail to stop, the stack will remain hot and consequently the circuit through resistor 176 will not be broken at the electrodes 25 182 and 183.

Moreover, if the hold tube 177 should remain 30 in its hot position wherein electrodes 182 and 183 establish a circuit therebetween, such as may occur if the thermostatic element 107 should break or the frictional slip connection between 35 the rod 83 and the member 90 should become inoperative, after either the limit control switch 178 or the room thermostat 155 are opened, then the ultimate safety resistor 176 will operate to 40 open the lockout tube 22.

The continued flow of current through heating element 176 will cause the bimetallic element 45 133 to warp and open lockout switch 22. Thus it will be noted that the ultimate safety feature of the circuits shown will open the main line or power supply circuit should the apparatus fail to operate whereby complete protection against 45 failure of any of the operating controls is provided.

Without further elaboration, the foregoing will so fully explain the gist of my invention that others may, by applying current knowledge, 50 readily adapt the same for use under varying 55 conditions of service, without eliminating certain features which may properly be said to constitute the essential items of novelty involved, which items are intended to be defined and secured to me by the following claims.

I claim:

1. Apparatus for a control system for oil burners or the like including fuel feeding means, actuating means therefor, and ignition means, said control apparatus comprising a switch for controlling said actuating means, a control circuit for controlling the operation of said switch, a transformer relay having a primary coil, a secondary coil in said control circuit, and a movable member influenced by the magnetic pull arising from the interaction of the magnetic fluxes produced by current flow through said coils for actuating said switch into operative position, and means for reducing the load on said primary coil to weaken the magnetic pull upon said movable member to hold the same in actuated position but insufficient upon release of said movable member upon current failure or reduction of current to restore it to actuated position. 75

2. Apparatus for a control system for oil burners or the like including fuel feeding means, actuating means therefor, and ignition means, said control apparatus comprising a switch for controlling said actuating means, a control circuit for controlling the operation of said switch, a transformer relay having a primary coil, a secondary coil in said control circuit, and a movable member influenced by the magnetic pull 5 arising from the interaction of the magnetic fluxes produced by the current flow through said coils for actuating said switch into operative position, means effective after initial operation of the burner for reducing the load on said primary coil and weakening the magnetic pull upon said movable member to hold the same in actuated position but insufficient upon release of said movable member upon current failure or reduction of current to restore it to actuated position, and thermostatic means responsive to the temperatures produced by the burner for controlling said control circuit.

3. Apparatus for a control system for oil burners or the like including fuel feeding means, actuating means therefor, and ignition means, said control apparatus comprising a switch for controlling said actuating means, a control circuit for controlling the operation of said switch, a transformer relay having a primary coil, a secondary coil in said control circuit, and a movable member influenced by the effective magnetic force produced by the inter-action of the magnetic fluxes resulting from current flow through both coils for actuating said switch, a resistance element adapted to be inserted in said control circuit to reduce the load on said primary coil and to weaken the effective magnetic force sufficiently to hold said member in actuated position but insufficient to move it to actuated position after release thereof upon current failure or reduction of current, a second switch for short-circuiting said resistance element until combustion is established at the burner, and thermostatic means adapted to respond to combustion conditions established by the burner for controlling the operation of said second switch.

4. Apparatus for a control system for oil burners or the like including fuel feeding means, actuating means therefor, and ignition means, said control apparatus comprising a switch for controlling said actuating means, a control circuit for controlling the operation of said switch, a transformer having a primary coil, a secondary coil in said control circuit, and a movable member influenced by the effective magnetic force resulting from the inter-action of the magnetic fluxes produced by current flow through the primary and secondary coils for actuating said switch, and means for reducing the current flow through the secondary coil to weaken the effective magnetic force sufficiently to hold said member actuated but insufficient to actuate said member after release thereof upon current failure or reduction of current, said means including a resistance element, a second switch for short-circuiting said resistance element until combustion is established at the burner and a third switch for inserting said resistance element in said control circuit when said second switch is opened.

5. Apparatus for a control system for oil burners or the like including fuel feeding means, actuating means therefor, and ignition means, said control apparatus comprising a switch for controlling said actuating means, a control circuit for controlling the operation of said switch, a

transformer having a primary coil, a secondary coil in said control circuit, a movable member influenced by the interaction of the magnetic fluxes produced by current flow through said coils for actuating said switch, and means for reducing the load on said primary coil to weaken the effective magnetic flux whereby the same will be only sufficient to hold said member actuated, said means including a resistance in circuit with the secondary coil, a second switch for short circuiting said resistance until combustion is established at the burner, a third switch for inserting said resistance in said control circuit when said second switch is opened, and thermostatic means adapted to respond to combustion conditions established by the burner for controlling the operation of said second and third switches.

6. Apparatus for a control system for oil burners or the like including fuel feeding means, actuating means therefor, and ignition means, said control apparatus comprising a switch for controlling said actuating means, a control circuit for controlling the operation of said switch, a transformer having a primary coil, a secondary coil in said control circuit, the interaction of the magnetic fluxes produced by the current flow through said coils serving to actuate said switch, and means for reducing the load on said primary coil to weaken the effective magnetic action upon said actuated switch but insufficient to effect release thereof, said means including a resistance in circuit with the secondary coil, a second switch for short circuiting said resistance until combustion is established at the burner, a third switch for inserting said resistance in said control circuit when said second switch is opened, and thermostatic means adapted to respond to combustion conditions established by the burner for controlling the operation of said second and third switches.

7. Apparatus for a control system for oil burners or the like including fuel feeding means, actuating means therefor, and ignition means, said control apparatus comprising a switch for controlling said actuating means, a control circuit for controlling the operation of said switch, a transformer having a primary coil, a secondary coil in said control circuit, means influenced by the temperatures produced by said burner for closing said control circuit, a movable member influenced by the inter-action of the magnetic flux produced by current flow through said coils for closing said switch, a resistance element adapted to be inserted in said control circuit to reduce the load on said primary coil after combustion is established at the burner, and means for inserting said resistance element including a recycling switch adapted to be opened upon establishment of combustion and a hold switch adapted to be closed prior to the opening of said recycling switch and to remain closed to hold said resistance element in said control circuit during normal operation of said control apparatus.

8. Apparatus for a control system for oil burners or the like including fuel feeding means, actuating means therefor, and ignition means, said control apparatus comprising a switch for controlling said actuating means, a control circuit for controlling the operation of said switch, a transformer relay having a primary coil, a secondary coil in said control circuit, a movable armature influenced by the magnetic flux diverted through the armature when current flows through the secondary coil for closing said switch, a resistance element adapted to be inserted in said

- control circuit to reduce the load on said primary coil after combustion is established at the burner, and means for inserting said resistance element in said control circuit upon establishment of combustion. 5
9. Apparatus for a control system for oil burners or the like including fuel feeding means, actuating means therefor, and ignition means, said control apparatus comprising a switch for 10 controlling said actuating means, a control circuit for controlling the operation of said switch, a transformer relay having a primary coil, a secondary coil in said control circuit, the interaction of the magnetic fluxes produced by the 15 current flow through said coils serving to close said switch, a resistance element adapted to be inserted in said control circuit to reduce the load on said primary coil after combustion is established at the burner, and means for inserting 20 said resistance element in said control circuit upon establishment of combustion.
10. Apparatus for a control system for oil burners or the like, including fuel feeding means, actuating means therefor, and ignition means, 25 said control apparatus comprising a switch for controlling said actuating means, a control circuit for controlling the operation of said switch, a transformer having a primary coil, a secondary coil in said control circuit, a movable member 30 influenced by the inter-action of the magnetic fluxes produced by current flow through said coils for closing said switch, a resistance element adapted to be inserted in said control circuit to reduce the load on said primary coil after 35 combustion is established at the burner, means for inserting said resistance element in said control circuit including a recycling switch and a hold switch, means responsive to combustion conditions of the burner for controlling the operation 40 of said recycling switch and said hold switch, a thermal element influenced by the heat effects of the current flow through said control circuit upon failure of said combustion responsive means to actuate said recycling switch and said hold 45 switch, and a switch in the circuit of said primary coil controlled by said thermal element.
11. Apparatus for a control system for oil burners or the like including fuel feeding means, actuating means therefor, and ignition means, 50 said control apparatus comprising a switch for controlling said actuating means, a control circuit, means comprising an electro-magnetic coil in the control circuit for controlling the operation of said switch, a resistor in said control circuit, thermal means influenced by the heat effects 55 of the current flow through said resistor in the said control circuit for rendering the system inoperative until manual intervention, combustion responsive means to operatively deenergize said resistor, and a normally open auxiliary control circuit having therein a boiler limit control and said resistor, said limit control being operated by an abnormal boiler condition resulting from 60 failure of said switch to open upon operative de- 65 energization of the electro-magnetic coil to energize said auxiliary circuit for rendering said system inoperative.
12. Apparatus for a control system for oil burners or the like comprising fuel feeding means 70 and actuating means therefor, said control apparatus comprising a switch for controlling the operation of said actuating means, a control circuit for controlling the operation of said switch, a transformer having its secondary coil in said 75 control circuit, said transformer including a 5 movable armature adapted to be operated upon current flow through said secondary coil for actuating said switch, a resistance element adapted to be inserted in said control circuit to reduce the flow of current through said secondary coil sufficient to keep said armature in operated position but to prevent return of said armature to operated position after release thereof upon current failure or reduction of current, means for inserting said resistance element in said circuit, 10 said means being responsive to the combustion conditions of the burner, and a second resistance element adapted to be connected in series relation with said first resistance element and said secondary coil when said control circuit is opened whereby to reduce the current flow through said secondary coil sufficiently to release said armature and open said switch. 15
13. Apparatus for a control system for oil burners or the like comprising fuel feeding means 20 and actuating means therefor, said control apparatus comprising a switch for controlling the operation of said actuating means, a control circuit for controlling the operation of said switch, a transformer having its secondary coil in said 25 control circuit, a movable armature adapted to be operated upon current flow through said secondary coil for actuating said switch, a resistance element adapted to be inserted in said control circuit to reduce the flow of current through 30 said secondary coil sufficient to keep said armature in operated position but to prevent return thereof to operative position when released therefrom upon current failure or reduction of current, means for inserting said resistance element in said circuit, said means being responsive to the combustion conditions of the burner, a second resistance element adapted to be connected in series relation with said first resistance element and said secondary coil when said control 35 circuit is opened whereby to reduce the current flow through said secondary coil sufficiently to release said armature and open said switch, and a thermal device influenced by the heat effects of the current flow through said second resistance element for opening the circuit through said switch upon failure of said armature to open said switch. 40
14. Apparatus for a control system for oil burners or the like, including fuel feeding means, actuating means therefor, said control system comprising: a switch for controlling said actuating means, a control circuit, means including a reactor in the control circuit for controlling the operation of said switch, an electro-thermal cut-off for deenergizing said system, a normally open auxiliary control system having therein a boiler limit control and the resistor of said electro-thermal cut-off, said limit control being operated by an abnormal boiler condition (resulting from 55 failure of said switch to open upon operative de-energization of said reactor) to energize said auxiliary circuit for rendering said system inoperative. 60
15. In combination, fuel supply controlling means, actuating means therefor, a switch normally biased to one of its positions for controlling said actuating means, an electrical device for controlling said switch and adapted to cause movement of said switch to its other circuit controlling position when energized, an electrically operated time switch for terminating operation of the system and including an operator which operates the time switch if the operator thereof is operatively energized for a predetermined 65 period of time. 70

- mined length of time, a main switch, circuit connections controlled by said main switch for energizing said device, a combustion responsive switch which opens upon cessation of combustion, a condition responsive switch which moves to a new circuit controlling position if said condition becomes abnormal by reason of failure of said actuating means switch to open upon deenergization of said device, and a circuit for said 5 operator of said electrically operated time switch controlled by said combustion responsive switch and the condition responsive switch when moved to said new circuit controlling position and independent of said main switch.
- 15 16. In combination, fuel supply controlling means, actuating means therefor, a switch normally biased to open position for controlling said actuating means, electromagnetic means for controlling said switch to move the same to closed 20 position against its bias, an electrically operated time switch for terminating operation of the system and including an operator which operates the time switch if the operator thereof is operatively energized for a predetermined length of 25 time, a main switch, circuit connections controlled by said main switch for energizing the electromagnetic means in a manner to cause closure of the first-named switch, a combustion responsive switch which opens upon cessation of 30 combustion, a boiler condition responsive switch which moves to a new circuit controlling position if said boiler condition becomes abnormal by reason of failure of said actuating means switch to open upon deenergization of the electromagnetic 35 means in such manner as to normally allow said first-named switch to open, and a circuit for said operator of said electrically operated time switch controlled by said combustion responsive switch and the boiler condition responsive switch 40 when moved to such new circuit controlling position and independent of said main switch.
17. In combination, fuel supply controlling means, actuating means therefor, a switch normally biased to one of its positions for controlling 45 said actuating means, electromagnetic means for controlling said switch and adapted to cause movement of said switch to its other circuit controlling position when at least a portion thereof is energized, an electrically operated time switch 50 for terminating operation of the system and including an operator which opens the time switch if said time switch operator is operatively energized for a predetermined length of time, a room thermostat, circuit connections controlled by said 55 room thermostat for energizing at least a portion of said electromagnetic means, a combustion responsive switch which opens upon cessation of combustion, a condition responsive switch which closes if said condition becomes abnormal 60 by reason of failure of said actuating means
- switch to move to its biased position upon deenergization of said portion of the electromagnetic means, and a circuit for said time switch operator independent of the room thermostat and controlled by said combustion responsive switch and condition responsive switch in series. 5
18. In combination, fuel supply controlling means, an actuator therefor, an actuator controlling switch normally biased to open position, an actuator controlling switch operator which causes closing of said actuator controlling switch against its bias when energized, an electro-thermal time switch for rendering the system inoperative and including a heating means, a main switch, combustion responsive switching means including a cold switch which opens upon the establishment of combustion and a hot switch which opens upon cessation of combustion, an initial energizing circuit for said actuating switch operator including said operator, main switch, cold switch and heating means in series, a maintaining circuit for said operator including said operator, main switch and hot switch in series, a switch which closes when a condition produced by the system becomes too high in value, and a circuit for the heating means controlled by said last named switch and said hot switch in series and independent of the main switch. 10 15 20 25
19. In combination, fuel supply controlling means, an actuator therefor, an actuator switch normally biased to open position, an electromagnetic coil in control of said actuator switch, an electro-thermal time switch for rendering the system inoperative and including a first and a second heating element, a main switch, combustion responsive switching means including a cold switch which opens upon the establishment of combustion and a hot switch which opens upon cessation of combustion, a heater condition responsive switch which opens if the value of 30 the heat condition to which it is responsive becomes too high, an initial energizing circuit for said electromagnetic coil including the main switch, a combustion responsive cold switch, said first heating element and said heater condition responsive switch in series, a maintaining circuit for said electromagnetic coil including the main switch, said heater condition responsive switch and combustion responsive hot switch in series, an energizing circuit for said second heating element controlled by the combustion responsive hot switch, and a shunt circuit for said second heating element controlled by the heater condition responsive switch and combustion responsive hot switch in series whereby the energizing circuit for said second heating element is completed only upon opening of said heater condition responsive switch while the combustion responsive hot switch is closed. 35 40 45 50 55 60
